G. W. OAKES

PLATE GLASS POLISHING MACHINE

Original Filed May 21, 1921

FIG.1.

FIG.2.

Patented Dec. 30, 1924.

1,520,766

UNITED STATES PATENT OFFICE.

GEORGE W. OAKES, OF CRYSTAL CITY, MISSOURI, ASSIGNOR TO PITTSBURGH PLATE GLASS COMPANY, A CORPORATION OF PENNSYLVANIA.

PLATE-GLASS-POLISHING MACHINE.

Application filed May 21, 1921, Serial No. 471,340. Renewed November 15, 1924.

To all whom it may concern:

Be it known that I, GEORGE W. OAKES, a citizen of the United States, and a resident of Crystal City, in the county of Jefferson

5 and State of Missouri, have made a new and useful invention in Improvements in Plate-Glass-Polishing Machines, of which the following is a specification.

The invention relates to plate glass polishing machines of the rotary type in which the table carrying the glass is rotated, and the runners, provided with the felt polishing discs, rest upon the glass and are rotated by reason of their frictional contact with the 15 glass. The invention has for its principal object the provision of an improved construction wherein a more uniform polishing of the glass on the table is secured and wherein the edge portion, which is often under polished in the ordinary machine, is given a better finish. One embodiment of 20 the invention is illustrated in the accompanying drawings, wherein:

Figure 1 is a plan view of the apparatus 25 shown in somewhat diagrammatic form, and Fig. 2 is a side elevation also somewhat diagrammatic in form for clearness of illustration.

Referring to the drawings, 1 is the table 30 on which the glass is secured, which table is mounted for revolution with its axle 2 (Fig. 2) and driven by any suitable means, such as the bevel gears 3 and 4. Mounted above the table in the usual framework 5 of 35 channel bars are the runners 6, 7, 8 and 9, such runners each comprising a cast iron framework mounted upon the axles 10, 11, 12 and 13. These runners are each provided with a plurality of polishing discs 14^a, felt 40 covered on the lower side and provided with spindles extending up through the body portions of the runners. These runners are ordinarily made of different sizes, as indicated in Fig. 1, and are rotated by reason of 45 the frictional contact of the felt discs with the glass upon the rotating table. The rotation of the table has a tendency to move the outer halves of the runners in one direction and the inner halves in the other, but since 50 the turning effect upon the outer halves of the runners is greater, due to the greater speed of the outer portion of the table as compared with its inner portion, the runners are rotated in the same direction as the table 55 itself. Suitable means are provided in a

machine of this kind for raising the runners to release the table, but such means are well known in the art and do not require description.

The construction as so far described is old 60 and well known in the art and the applicant's invention consists in the use of supplemental runners, in the present instance two in number, such runners being designated in the drawings with the numerals 14 65 and 15. These runners are similar in general construction to the runners heretofore described except in the matter of size. They are each provided with a plurality of felt faced discs 16, similar to the discs 14^a, and 70 the two runners are mounted on axles 17 and 18 mounted to rotate in the framework 5. These runners are power driven, however, in that pulleys 19 and 20 are provided at the 75 upper ends of the shafts and connected by means of belts 21 and 22 with other pulleys 23 and 24 mounted upon the upper ends of the shafts 10 and 12. Due to the small size 80 of the runners, they will not rotate themselves by reason of the contact of the discs with the glass, so that this driving arrangement is necessary in order to secure the desired polishing effect. The advantage resulting from the use of these supplemental or auxiliary runners is that a better polishing effect is secured upon that portion of the 85 glass at the periphery of the table. It has been found that with a polishing machine such as that illustrated in Fig. 1 and employing two or more self driven runners, 90 there is a tendency of the glass to be under polished on the outer portions of the table, and these auxiliary runners supply the necessary additional polishing effect. The driving of these small runners from the large 95 runners 6 and 8 is a matter of convenience and also adds to a certain extent to the efficiency of the large runners since it tends to slow down their movement of rotation and thus increases the frictional effect between 100 the discs of these runners and the glass upon the table. The invention is not, however, limited to the driving of the small runners from the large ones and is not limited to the use of two auxiliary driven small runners or 105 to the use of auxiliary driven small runners in connection with a four runner polisher of the type illustrated in Fig. 1, as the smaller driven runners might be used to advantage in connection with a polishing table 110

carrying less than four self driven runners. At the present time, however, the table employing four self driven polishing runners is regarded as the best practice, and on such a table the best results are secured by using two small driven runners so that the construction just as illustrated and described shows the best method of carrying out the invention.

10 What I claim is:

1. In combination in a plate glass polishing machine, a circular driven table adapted to carry the glass, a pair of circular polishing runners whose combined diameters approximate that of the table mounted above the table with their polishing surfaces in opposition to the surface of the table and adapted to rest upon the glass on the table and be rotated by their frictional contact therewith, a pair of smaller polishing runners located with their axes of rotation

adjacent the edge of the table, and means for rotating the smaller runners from the larger ones.

2. In combination in a plate glass polishing machine, a circular driven table adapted to carry the glass, a plurality of circular polishing runners of relatively large diameter mounted above the table with their polishing surfaces in opposition to the surface of the table and adapted to rest upon the glass on the table and be rotated by their frictional contact therewith and together covering the major portion of the table, a plurality of smaller runners located with their axes of rotation adjacent the edges of the table, and means for driving the smaller runners from the larger ones.

In testimony whereof, I have hereunto subscribed my name this 17th day of May, 1921.

GEORGE W. OAKES.
